UNITED STATES PATENT OFFICE.

FREDERICK S. FOLGER, OF FLUSHING, AND HENRY W. ALTMAN, OF COLLEGE POINT,
NEW YORK.

SPRING WINDING MACHINE.

Application filed November 20, 1925. Serial No. 70,352.

This invention relates to winding machines and in particular to a type adapted to wind devices wherein are embodied springs, which require considerable winding in order to 5 coil the same into operating position.

The particular object of the invention is to provide an efficient machine and a plurality of chucks therefor, which can be used to wind up a series of spring operated devices such as toys, window shade rollers and the like.

A further object of the invention is to so construct the machine that it can be set up in any desired position and can be operated by hand to efficiently wind up a device embodying a spring.

A further object of the invention is to construct a machine of this character which will have few parts, can be manufactured at 20 a small cost and which will last indefinitely.

A further object of the invention is to provide a number of chuck pieces which will engage the parts of the device to be wound, which carries the spring whereby said 25 spring may be wound by a turning movement of the chuck, the machine being arranged to multiply the speed of winding, which is originally imparted to the machine by an operator.

Referring to the drawings, wherein a preferred embodiment of our invention has been shown;

Figure 1 is a view in front elevation of a machine constructed in accordance with 35 our idea, the face of the chuck carried by said machine being shown.

Figure 2 is a view in vertical section taken on the line 2—2 of Figure 1 and shows the interior section of the machine and illustrating how the power applied thereto by an operator is transferred to the 40 chuck to perform the winding operation.

Figure 3 is a face view of a chuck, used for winding up the end of a window shade roller or the like.

Figure 4 is a section taken on the line 4—4 of Figure 3, showing the shape of the slot in the chuck.

Figure 5 is a face view of a modified 50 form of chuck having a conical depression therein which renders the placing of the device to be wound possible with a minimum of time and effort.

Figure 6 is a section taken on the line 55 6—6 of Figure 5.

Figure 7 is a face view of another modification of chuck made in two parts and showing an interchangeable feature.

Figure 8 is a section taken on the line 8—8 of Figure 7 showing the construction 60 of the chuck.

Figure 9 is a face view of a still further form of modification of chuck which prevents unwinding of the spring by a reverse rotation of the chuck contrary to the winding movement, and

Figure 10 is a section taken on the line 10—10 of Figure 9 showing the construction 65 of the chuck.

Referring to the drawings in detail, 70 5 indicates the machine frame, having a depending portion 6 in which is threaded the screw 7, carrying at its upper end the jaw 8 and at its lower end, the finger piece 9, the jaw 8 being adapted to engage the under side 75 of a table edge 10 upon the top of which rests the projected foot portions 11 which are formed integral with the frame 5. The upper portion of the frame is formed to provide a circular housing 12, having cast 80 therein at its center, the hub 13, in which is journaled the drive shaft 14, which carries at its outer end, the operating handle 15, the handle being suitably held thereon through the medium of the nut 16. 85

The inner end of the shaft 14 is threaded as at 17 and carries thereon a driving gear 18, which is positioned on said driving shaft between a collar 19 and a lock nut 20, the face of the housing 12 is closed through the 90 medium of the snap cover 21 which is held in place at its lower end by the fixed pin 22 and engages at its upper end in the notch 23 formed in the under side of the housing 24 which is cast integral with the housing 95 12 at the top thereof. The housing 24 is closed through the means of the cover 21 and supports therein the stub shaft 26 upon which is mounted a pinion 27 in engagement with the gear 18 and driven thereby, the stub shaft 26 being squared at its forward end as at 27 to receive a chuck 28, the chuck being held in position by a set screw 29.

Operation of the handle 15 will, through 105 the gear 18 and pinion 27, revolve the stub shaft 26 at a high rate of speed, so that the chuck 28 will revolve rapidly and thereby wind up the spring in any device having a spring carrying or winding element. In 110

Figure 2, we have illustrated the end of a shade roller 30, the spring shaft thereof being indicated as at 31 and through the medium of which, the spring of the shade roller, not shown, is wound.

In the chuck 28, we have shown an undercut slot 32 into which is slid the face plate 33 and held therein by the screws 34, the center of the face plate being raised as at 35 and being cut to provide a cross-shaped slot 36 into which the end 31 of the shade roller shaft can be inserted. By making this cross-shaped slot of such formation, no adjustment of the handle 15 will be necessary in order to bring the chuck into position for insertion of the end of the shade roller shaft, thereby saving time and adjustment of the shade roller relative to the chuck 28. In order to adapt the machine for use in winding up various devices, we provide therefor, a plurality of chucks and in Figures 3 and 4, have shown a chuck embodying a cross-shaped slot 37, the sides of which are tapered as at 38 to allow for various thicknesses of the end of spring winding shafts, such, for instance, as the finger pieces used on mechanical toys to wind the same up.

In Figures 5 and 6, we have shown another form of chuck having a depression 39 therein, at the bottom of which is provided, the cross-shaped slot 40. This depression 39 is tapered so that when the end of a spring shaft is placed thereagainst, it will automatically find its way into the cross-shaped slot 40.

In Figures 7 and 8, we have shown a chuck 41 having fastened on the face thereof a slotted plate, which functions somewhat after the manner of the chuck illustrated in Figures 5 and 6, the plate 42 having a depression 43 therein and also a cross-shaped slot 44.

In Figures 9 and 10, we have shown a chuck in the nature of a cup 45 having two cam-like pieces, set therein and being so cut and shaped that they will provide a slot 47 between them into which may be inserted the end of a shaft to be wound. The opposite diagonal parts 48 and 49 of said pieces being sloped downwardly so that if the chuck is

given a reverse rotation, the spring shaft indicated as at 50 will ride up on the pieces and will not be unwound. These chucks may be placed on the end of the driven shaft 55 by any suitable means. It will be evident therefore, that we have provided a machine which may be used with a number of chuck pieces for use in winding up the spring operated toys, roller shades and in winding the 60 springs themselves about a mandrel during manufacture, and a machine which will multiply the power of an operator and will wind the devices, toys or the like rapidly and efficiently, thereby reducing the cost of 65 the articles with a resulting benefit to the users.

Also it will be evident that we have provided a machine, which can be set up in any desirable position or place, such, for instance, as in the toy department of stores where mechanically operated toys have to be wound for demonstration and in any other place, such as in a shade roller manufacturing plant where springs are wound 75 up so that the shade roller will have the proper adjustment when placed in position.

While we have illustrated and described our invention with some degree of particularity, we realize that in practice various 80 alterations therein may be made and therefore, we reserve the right and privilege of changing the form of the details of construction or otherwise altering the arrangement of the correlated parts without departing from the spirit of the invention or the scope of the appended claim.

Having thus described our invention, what we claim as new and desire to secure by United States Letters Patent is:—

The combination with a machine having a driven shaft and a speed multiplying gear arrangement of a chuck secured to said shaft, said chuck having a cross-shaped slot therein for accommodation of a shaft end to be wound, and a conical depression in said chuck whereby the shaft end may be guided into said slot.

In testimony whereof we affix our signatures.

FREDERICK S. FOLGER. [L.S.]
HENRY W. ALTMAN. [L.S.]
